UNITED STATES PATENT OFFICE

96,382

DESIGN FOR A DOLL

Mollye Goldman, Philadelphia, Pa.

Application May 7, 1935, Serial No. 56,711

Term of patent 14 years

To all whom it may concern:

Be it known that I, Mollye Goldman, a citizen of the United States, residing at Philadelphia, in the county of Philadelphia and State of Pennsylvania, have invented a new, original, and ornamental Design for Dolls, of which the following is a specification, reference being had to the accompanying drawing, forming a part thereof.

Fig. 2 is a rear view of the same.

I claim:

The ornamental design for a doll, as shown.

MOLLYE GOLDMAN.
